DESIGN FOR A SUPPORT FOR COLOGNE BOTTLES

Charles H. Foster, New York, N. Y., assignor to Babs Creations, Incorporated, New York, N. Y., a corporation of New York

Application April 9, 1941, Serial No. 100,259

Term of patent 7 years

To all whom it may concern:

Be it known that I, Charles H. Foster, a citizen of the United States, residing in New York city, in the county of New York and State of New York, have invented a new, original, and ornamental Design for a Support for Cologne Bottles, of which the following is a specification, reference being had to the accompanying drawing, forming a part thereof.

In the drawing:

I claim:

The ornamental design for a support for cologne bottles, as shown.

CHARLES H. FOSTER.
